UNITED STATES PATENT OFFICE.

GEORGE E. KARL, OF CLEVELAND, OHIO, ASSIGNOR TO THE DUNHAM COMPANY, OF BEREAL, OHIO, A CORPORATION OF OHIO.

LAWN-ROLLER.

1,120,820.

Specification of Letters Patent. Patented Dec. 15, 1914.

Application filed February 16, 1914. Serial No. 819,078.

To all whom it may concern:

Be it known that I, GEORGE E. KARL, a citizen of the United States, resident of Cleveland, county of Cuyahoga, and State 5 of Ohio, have invented a new and useful Improvement in Lawn-Rollers, of which the following is a specification, the principle of the invention being herein explained and the best mode in which I have contemplated 10 applying that principle, so as to distinguish it from other inventions.

My invention relates to lawn-rollers and particularly to lawn-rollers in which the heads are each provided with a central opening surrounded by an outwardly extending flange united by welding to the ends of an axle tube extending through such openings.

Its object is to provide a structure in which the joint formed by such described 20 union will be protected against abrasion resulting from the frictional action of contiguous relatively moving parts.

The said invention consists of means hereinafter fully described and particularly set 25 forth in the claims.

The annexed drawing and the following description set forth in detail certain means embodying my invention, the disclosed means, however, constituting but one of 30 various mechanical forms in which the principle of the invention may be applied.

In said annexed drawing:—Figure 1 represents an end elevation of a lawn-roller embodying my invention, showing only a fragmentary portion of the handle. Fig. 2 represents an axial section of the roller showing part of the handle and the axle-rod in elevation. Fig. 3 represents an axial section of a fragmentary portion of the roller, upon 40 an enlarged scale, showing the details of construction of the bearing parts of one of the handle members, and the contiguous parts of the body-portion or drum of the roller.

The illustrated device comprises a main portion or drum 1, and the handle 2. Said drum consists of a cylindrical shell 3 provided with two end heads 4, 4. Each head is formed with an outwardly extending flange 5 welded to the contiguous end of the shell and with a central opening 6 surrounded by an outwardly extending short annular flange 7 welded to the contiguous end 8 of an axle tube or sleeve 9, as shown in Fig. 3, 55 the two together forming an outwardly

extending flange. Extending through said sleeve with its end extending considerably beyond the ends of said flanges 7, is an axle-rod 10. The projecting ends of this rod form journals for roller-bearings 11 60 mounted in the handle-members 12, 12, of the handle 2.

Placed intermediately of each roller-bearing and the welded joint formed between the adjacent flange 7 and tube end 8, is a 65 washer 13 formed with a central opening 14 of a diameter sufficiently great to permit the washer to snugly fit upon the rod 10. Surrounding said opening 14 is a countersunk portion or depression 15 upon its inner 70 side. The thickness of the washer is made such that the said depression may be made of a depth such that the said joint may project into said depression without coming into contact with the washer while the inner 75 surface of the latter is engaging the contiguous surface of the head 4, as shown in Fig. 3. Between the roller-bearing and said washer an auxiliary washer 16 may be placed if desired, and an outer washer 17 is 80 provided and held on the rod by means of a cotter-pin 18, thus retaining the rollers 19 of said roller-bearing.

By means of the above described construction, it will be seen that abrasion of the 85 welded joints formed by the flanges 5 and tube ends 8 is prevented and all wear due to movement of parts, other than the rollers and journals on rod 10, transmitted to the washer 13 and the heads 4, thus preventing 90 the abrasion of said joint and eliminating the danger of leakage which might result therefrom.

Having fully described my invention, what I claim and desire to secure by Letters 95 Patent is:—

1. In a lawn-roller, the combination of a roller-head having a central, outwardly-projecting flange; a journal-member co-axial with said flange; a bearing-member 100 mounted upon said journal-member; and a washer interposed between said head and said bearing-member and detached from said head; said washer being formed with an annular groove upon its inner face; said 105 flange projecting into said groove.
2. In a lawn-roller, the combination of a roller-head having a central, outwardly-projecting flange; a journal-member co-axial with said flange; a bearing-member 110

mounted upon said journal-member; and a separating member interposed between said bearing-member and head adapted to engage the latter while out of contact with the 5 end of said flange.

3. In a lawn-roller, the combination of a roller-head having a central opening surrounded by an outwardly projecting flange; an axle projecting outwardly through said 10 opening and beyond said flange; a bearing-member mounted upon the outwardly projecting portion of said axle member; and a washer interposed between said bearing-member and flange; said washer formed 15 with a central opening through which said

axle-member projects, of less diameter than the outer diameter of said flange and formed with a depression upon its inner surface adapted to receive said flange; the depth of said groove being such that the washer may 20 engage the adjacent surface of said head while out of contact with the end of said flange.

Signed by me, this 12th day of February, 1914.

GEORGE E. KARL.
